Patented June 24, 1919.

UNITED STATES PATENT OFFICE.

ALBERT AUGUSTUS MOSS, OF NEWARK, NEW JERSEY.

WRENCH.

1,307,592.

Specification of Letters Patent. Patented June 24, 1919.

Application filed March 27, 1919. Serial No. 285,416.

To all whom it may concern:

Be it known that I, ALBERT AUGUSTUS Moss, a citizen of the United States, residing at Newark, in the county of Essex and 5 State of New Jersey, have invented a new and useful Wrench, of which the following is a specification.

The device forming the subject matter of this application is a wrench, and the invention aims to provide novel means for 10 holding the movable jaw in adjusted positions with respect to the fixed jaw.

It is within the province of the disclosure to improve generally and to enhance the 15 utility of devices of that type to which the invention appertains.

With the above and other objects in view, which will appear as the description proceeds, the invention resides in the combination 20 and arrangement of parts and in the details of construction hereinafter described and claimed, it being understood that, within the scope of what is claimed, changes in the precise embodiment of the invention can be 25 made without departing from the spirit of the invention. In the accompanying drawings:—

Figure 1 shows in side elevation, a wrench constructed in accordance with the invention, parts being shown in section and parts being broken away; Fig. 2 is an elevation wherein the wrench is viewed at right angles to the showing of Fig. 1; Fig. 3 is a cross section on the line 3—3 of Fig. 1; Fig. 4 is a cross section on the line 4—4 of Fig. 1.

The numeral 1 denotes a handle carrying a shank 2 provided with a fixed jaw 3. On its sides, the shank 2 is supplied with outstanding ribs 4 having teeth 5 on their forward edges, although the forward edges of the ribs may be roughened in any desired way. The ribs 4 extend diagonally of the shank 2, and, consequently, form an unusually effective reinforcement for the shank.

45 The numeral 6 designates a movable jaw adapted to coöperate with the fixed jaw 3, the movable jaw constituting part of a slideable member including a bottom portion 7 connected with the movable jaw by side arms

50 8. The movable jaw 6 and its bottom portion 7 are provided with openings 9 receiving the shank 2 slidably. There are grooves 10 in the parts 6, 7 and 8, the grooves being elongated transversely of the wrench, so as to 55 receive the inclined ribs 4. In its forward portion, the movable jaw 6 has an opening

11. Fingers 12 project forwardly from the bottom member 7. One end of a lever 14 extends into the opening 11 and is mounted therein on a pivot element 15 carried by the 60 jaw 6. The lever 14 is offset as shown at 17, to form a grip 16. Intermediate its ends, the lever 14 is supplied with an inwardly projecting boss 18 having a slot 19 elongated longitudinally of the wrench. The numeral 65 20 marks a U-shaped latch straddling the grip 16 and adjustable longitudinally of the grip. Side portions of the latch 20 are supplied with projections or dogs 21 adapted to 70 coact with the teeth 22 of racks formed on the fingers 12 which project from the member 7. A pin 23 is mounted transversely in the grip 16 and is received slidably at its ends in slots 24 formed in the side portions of the U-shaped latch 20. Consequently, the 75 latch 20 is mounted for right line sliding movement on the shank 16, so that the dogs 21 may be moved into and out of engagement with the teeth 22 on the fingers 12. The latch 20 is equipped with an internal 80 recess 25 wherein is located a compression spring 26, one end of which engages an abutment 27 extended from the grip 16, the other end of the spring abutting against the latch 20 at the end of the recess 25. Clearly, the 85 spring 26 forms a means whereby the dogs are engaged normally with the teeth 22 on the fingers 12.

The invention comprises a retainer which is H-shaped in cross section, the retainer including a web 28 extended longitudinally of the wrench, inner flanges 29 and outer flanges 30, the flanges 29 and 30 extending transversely of the wrench. The inwardly projecting flanges 29 receive the forward edge of the shank 2, the web 28 lying in front of the shank. The ends of the flanges 29 and 30 are engaged with the lower edges of the fingers 12, slidably, to guide the retainer 90 as the same moves transversely of the shank 2. On their edges, inwardly projecting flanges 29 are provided with teeth 31 adapted to coöperate with the teeth 5 on the ribs 4. The boss 18 on the intermediate portion 95 of the lever 14 extends between the outwardly projecting flanges of the retainer, and these flanges carry the ends of a pin 32 slidably received in the slot 19 of the boss 18. It may be observed, at this point, that 100 the bend 17 of the lever 14 is slidably received between the outwardly extended 105 110

flanges 30, lateral movement of the lever thus being limited.

In practical operation, the latch 20 is retracted by thumb pressure so that the projections or dogs 21 do not engage with the teeth 22. Then, the lever 14 may be swung inwardly or outwardly on its pivotal mounting 15, carrying with it the H-shaped retainer, the teeth 31 on the flanges 29 of the retainer being moved out of engagement with the teeth 5 on the ribs 4. Then, the jaws 6 may be shifted toward and away from the jaw 3. The lever 14 may be swung inwardly, to cause the teeth 31 on the retainer to engage with the teeth 5 on the ribs 4, and when the latch 20 is released, the dogs 21 will coat with the teeth 22 to hold the lever 14 and the H-shaped retainer in such a position that the teeth 31 and 5 will co-operate, thereby maintaining the jaw 6 in any position to which it may have been adjusted.

Having thus described the invention, what is claimed is:—

1. A wrench comprising a shank having a fixed jaw; a movable jaw slidable on the shank and provided with teeth on its inner end; a retainer slidable in the movable jaw transversely of the shank, the shank and the retainer having interengaging elements; a lever pivoted to the movable jaw and to the retainer; and a spring actuated latch mounted on the lever and movable longi-

tudinally of the lever, the latch coacting with the teeth of the movable jaw.

2. A wrench comprising a shank having side ribs and provided with a fixed jaw; a movable jaw slidable on the shank; a retainer slidable in the movable jaw and of H-shape in cross section, the retainer comprising outwardly extended flanges, and inwardly extended flanges receiving the shank and coöperating with the ribs; and a lever pivoted to the movable jaw, the lever including two parts received between the outwardly extended flanges, one of said parts being pivoted to the outwardly extended flanges.

3. A wrench comprising a shank having side ribs extended diagonally of the shank, and provided with a fixed jaw; a movable jaw slidable on the shank; a retainer slidable in the movable jaw and including flanges receiving the shank and coöperating with the ribs; a lever pivoted to the movable jaw and pivoted to the retainer; and a latch forming a releasable connection between the lever and the movable jaw.

In testimony that I claim the foregoing as my own, I have hereto affixed my signature in the presence of two witnesses.

ALBERT AUGUSTUS MOSS.
